UNITED STATES PATENT OFFICE.

FRANK S. GREENE, OF CLEVELAND, OHIO.

ARITHMETICAL PUZZLE BLOCKS.

Application filed June 18, 1921. Serial No. 478,504.

To all whom it may concern:

Be it known that I, FRANK S. GREENE, a citizen of the United States, residing at Cleveland, in the county of Cuyahoga and State of Ohio, have invented a certain new and useful Improvement in Arithmetical Puzzle Blocks, of which the following is a full, clear and exact description, reference being had to the accompanying drawings.

10 This invention relates to arithmetical block puzzles or games involving numerical arrangements of the type known as magic squares.

It is the object of this invention to present an interesting but rather intricate mathematical problem in such a manner that the various mathematical relationships can be visually demonstrated by a method simple enough to be readily learned by even very young children, and to encourage the exercise of the faculties of observation and deduction by providing puzzles or problems of gradually increasing difficulty, for the solution of which intelligent observation in connection with the simpler problems is essential, the series of problems presenting all the data necessary for the complete solution or explanation of the principles upon which the puzzle is based. More specifically, it is the object of this invention to provide a numerical block puzzle or game involving a simple method of placing the blocks with their numerals in magic square formation, the demonstration of said method providing excellent entertainment and exciting curiosity and wonder, thus providing for young children an interesting game in which they acquire proficiency in mental arithmetic and also providing a puzzle or game which appeals to older children and adults by exciting curiosity as to the underlying principles and invites systematic study thereof by providing means whereby a series of distinct problems may be worked out, intelligent observation in connection with the various problems suggested, furnishing sufficient data on which to base a complete explanation of the whole puzzle, thus providing a puzzle or game which will provide amusement to all and as much mental exercise as the individual cares to indulge in, the complete problem providing a rather severe test of the individual's reasoning capacity.

In the drawing forming a part of this specification,

Figure 1 is a view showing the opposite faces of a set of sixteen blocks.

Fig. 2 is a top view of a receptacle for receiving the blocks.

Fig. 3 is a transverse section through the box with the cover in place.

Figs. 4, 5 and 6 show one method of arranging the blocks in the receptacle with reference to the designs carried thereby.

Fig. 7 shows the blocks of Fig. 6 turned over in the cover of the receptacle to expose the numerals.

Fig. 8 shows a somewhat different method of arrangement.

Fig. 9 shows the blocks of Fig. 8 turned over in the cover of the receptacle.

Figs. 10 and 11 are detail views of a block with a detachable numeral plate.

Fig. 12 is a view showing a method of arranging the blocks by means of the designs thereon to receive a new set of numerals.

Fig. 13 is a view showing the blocks of Fig. 12 turned over into the cover of the receptacle and having a new set of numerals attached thereto.

Figs. 14 and 15 show an arrangement of the blocks according to the designs carried thereby and the arrangement of numerals corresponding thereto.

Sixteen blocks bearing numerals 1 to 16 and certain characters or designs on the faces opposite the numerals as shown in Fig. 1 fit in a receptacle A which is divided into sixteen equal squares, each equal in size to one of the blocks.

Relative positions of the various block receiving squares may be determined by reference to the vertical and horizontal rows or by reference to one of these rows and a diagonal row. Only two of the diagonal rows however include four squares. The vertical rows, as well as the horizontal rows, are mutually exclusive. In order to provide four mutually exclusive diagonal rows, the squares traversed by the heavy single line *a* are considered in one diagonal row and the squares traversed by the double lines *b* are considered another diagonal row. Hereafter the expression "in line with" means in the same horizontal vertical or diagonal row as defined above.

As shown in Fig. 1, the blocks bearing numerals 1 and 16 have uncolored designs, 1 a plain triangle, and 16 the same triangle

divided into four smaller triangles. These two blocks are the lead blocks; i. e. the first two to be placed in the square, and are therefore preferably given fanciful easily remembered names such as "Jazz" and "Jinx." 5 Four blocks bearing numerals 8, 12, 14 and 15 have large triangles colored respectively, yellow, brown, green and red. Six blocks bearing numerals 4, 6, 7, 10, 11 and 13 each 10 have two smaller triangles colored to correspond with two of the large single colored triangles. These six blocks show every possible combination of two out of four colors. The four remaining blocks 2, 3, 5 and 9 each 15 have three colored triangles bearing three of the four colors above named. These four blocks show all the combinations of three out of four colors.

To arrange the blocks to form a magic 20 square, the two lead blocks "Jazz" and "Jinx" may be placed anywhere in the same diagonal line and the four single colored triangle blocks are placed in line with "Jazz" but out of line with "Jinx," as shown 25 in Fig. 4. The six double triangle blocks are then placed so that each of the two triangles is in line horizontally or vertically with the large triangle of the same color. As shown in Fig. 5, the block having the red and 30 yellow triangles is in the same horizontal line with the blocks having the large red and large yellow triangles, the block bearing the two triangles colored brown and green in the same vertical line with the 35 two blocks bearing the large brown and green triangles, the block having two triangles colored brown and red is in the same horizontal line as the large brown triangle and in the same vertical line as the large 40 red triangle, and the three remaining double triangle blocks have similar positions with respect to the two large triangle blocks bearing the two colors of each. There now remain four vacant places to be filled by the four 45 blocks having three colored triangles. For each vacant place note the three colors present in the vertical or horizontal line through the vacant space which does not include the "Jinx" block, and insert in 50 each place the block bearing the three colors present in this line. In the second horizontal line of Fig. 5 the colors brown, red and yellow occur. The block bearing brown, red and yellow triangles fills out this 55 line (see Fig. 6). In the first vertical line, Fig. 5, the colors red, brown and green occur and block bearing colors red, brown, and green fills out the line. In the third vertical line yellow, brown and green occur 60 and block bearing yellow, brown and green triangles fills out the line.

Fig. 7 shows the blocks of Fig. 6 turned over into the cover B of the receptacle. It will be noted that each vertical, horizontal 65 and diagonal line totals 34.

Fig. 8 shows a somewhat more difficult arrangement. According to this view the "Jazz" and "Jinx" blocks have been placed in the same horizontal line, the four large colored triangles have been placed in line 70 vertically and diagonally with the "Jazz" block, the six double triangle blocks have been placed with each triangle in line vertically or diagonally with the large triangle of the same color, and the four three-color blocks each fills out a vertical or diagonal line in which the three colors are already present.

A general statement of the rule of arrangement is that the "Jazz" and "Jinx" 80 blocks must be placed in the same line with each other vertically, horizontally or diagonally. The four single color blocks are then placed in line with "Jazz" but out of line with "Jinx." The six double color blocks 85 are then placed with each of their colored triangles in line with the big triangle of the same color along one of the two classes of lines other than that upon which both "Jazz" and "Jinx" are located; i. e. if "Jazz" 90 and "Jinx" are on a diagonal line the double triangle blocks are lined up along vertical and horizontal lines; if "Jazz" and "Jinx" are on a horizontal line the double triangle blocks are lined up along vertical and 95 diagonal lines, and if "Jazz" and "Jinx" are on a vertical line the double triangle blocks are lined up along horizontal and diagonal lines. When all the double colored blocks are placed, there will remain four 100 places to be filled with the three-color blocks. One of the three lines through each vacant place will contain one large triangle and two double triangle blocks, and three colors will appear on these three blocks. The 105 block bearing the three colors appearing in such a line fills out the line.

The "Jazz" block can be placed in any one of the sixteen squares in the box, the "Jinx" block can then be placed in any one 110 of nine squares and the four single color blocks can be arranged in any order in the four squares determined by the position of the two leader blocks. Since there are 24 different ways of arranging four things in 115 four places it follows that the above rule covers $16 \times 9 \times 24$ or 3,456 different magic square arrangements.

It will be noted that the location of all the blocks in the square is positively determined 120 when the two leader blocks and the four single blocks have been placed. In Figs. 7 and 9 the blocks bearing numerals 8 and 9 have been marked A and B respectively, and the four blocks bearing numerals 1, 10, 11 125 and 13 have each been marked a. The blocks marked A and B are lead blocks corresponding to "Jazz" and "Jinx" and the four blocks marked a correspond to the four single triangle blocks. Whenever A and B 130

are placed in line with each other and the four *a* blocks are placed in line with each other and the four *a* blocks are placed in line with A but out of line with B it is possible 5 to place the remaining blocks to form a magic square. Each arrangement is a problem in itself but intelligent observation of the arrangements produced by the methods first described will enable one to quickly fill 10 in the ten remaining blocks in their proper places for any such arrangement of the six marked blocks.

In order to make fuller use of the possibilities inherent in the system of markings 15 above described the blocks *c* may be provided with detachable number plates *d* as shown in Figs. 10 and 11. As many number plates as desired may be used.

Fig. 12 shows the blocks arranged to receive 20 a set of numerals. In this arrangement which might be termed the reverse arrangement, the "Jazz" and "Jinx" blocks are placed in the same diagonal line with the further limitation that they must both be in squares 25 bordering opposite sides of the box or both be in inside squares. The four single color blocks are then placed in line with "Jinx" but out of line with "Jazz." The double color blocks are then each lined up in vertical or horizontal lines with the two blocks 30 having large triangles of the two colors not on the two-color block. Each of the three color blocks then fills out a line in which the one color absent therefrom occurs twice; i. e. in the second horizontal line of 35 Fig. 10 the color green occurs twice. The block having colors brown, red, and yellow fills out this line. Under the above rule of arrangement one of the leader blocks may 40 be placed in any one of the sixteen squares in the box. The position of the second leader block is fixed by the first, but the four single color blocks can be arranged in any one of 24 different ways. The total number 45 of arrangements under the above rule is therefore 16×24 or 384. If the numerals 1 to 16 be applied in consecutive order to the blocks arranged according to any one of the 384 reverse arrangements, the rule 50 of arrangement described in connection with Figs. 4 to 9 will still hold good for forming magic squares.

Other groups of numerals other than the numerals 1 to 16 may be attached to the 55 blocks. Sixteen consecutive terms of any series which fulfills the following conditions may be selected:

The differences between successive terms are $W X Y Z$ where $W X Y$ and Z are each 60 positive or negative integers and the series progresses as follows: $W, X, W, Y, W, X, W, Z, W, X, W, Y, W, X, W$.

Select any number for the first term, assign arbitrary values to $W X Y$ and Z , 65 add W to first term to get second, X to

second to get third, W to third to get fourth, and Y to fourth to get fifth, etc., as indicated above. In Fig. 13, W equals 3, X equals 2, Y equals 2, Z equals 12. Another way of stating the rule is that when the 16 70 numbers are arranged in a square in consecutive order as in Fig. 13 there must be a constant difference between the adjacent numerals in any two parallel columns taken vertically or horizontally, and the difference 75 between numerals in the first and second columns must equal the difference between numerals in the third and fourth columns, taking columns both vertically and horizontally. The differences $W X Y$ and Z 80 may be all equal in which case the numbers are successive terms of an arithmetic series, or any two or three of the four differences may be equal.

The numerals of the series shown in Fig. 85 13 are shown applied to the blocks in consecutive order beginning at the upper left hand corner. In Fig. 14 the blocks with the numerals attached as indicated in Figs. 12 and 13 are arranged in magic square 90 order similar to that shown in Figs. 4 and 6. Fig. 15 shows the blocks of Fig. 14 turned over into the cover of the receptacle. The numerals as arranged in Fig. 15 total 100 on every vertical horizontal and diagonal 95 line.

After a player has learned to readily build any of the various magic square arrangements with the aid of the six marked numeral blocks only, the next problem is to 100 formulate a rule whereby any numeral can be placed in any square, its complementary numeral in any of the nine squares aligned with the first numeral, and the four numerals which are to be placed in line with the first numeral and out of line with its complementary numeral determined, so that any of the 3456 arrangements can be made without the aid of any system of marking. The 105 solution of the series of problems above 110 suggested will furnish the data necessary for a complete mathematical explanation of the puzzle.

What I claim is:

1. A set of puzzle blocks comprising sixteen blocks bearing numerals representing successive terms of a recurring series, two of said blocks having distinguishing designs thereon, and four other blocks having designs distinguishing them from the first 120 two blocks, said four blocks bearing numerals which have a definite mathematical series relationship with the numerals on the two first mentioned blocks substantially as described.

2. A set of puzzle blocks comprising sixteen blocks, each having a distinguishing design thereon, two of said blocks bearing designs that readily distinguish them from each other and from all the other blocks,

- four of said blocks bearing designs which differ from each other but identify them as a group, six of said blocks bearing designs involving different combinations of distinguishing features of two of said group of four blocks and the four remaining blocks bearing different combinations of distinguishing features of three of said group of four blocks.
- 10 3. The set of puzzle blocks as set forth in claim 2 together with detachable and interchangeable numeral plates therefor.
4. In a set of puzzle blocks, sixteen blocks bearing numerals representing successive terms of a recurring series, two of said blocks whose numerals have a complementary relationship having designs thereon which distinguish them from each other and from all the other blocks, a group of four blocks 20 whose numerals have a definite series relationship with respect to the two first mentioned blocks and which have designs thereon distinguishing them from each other, but which identify them as a group, a second set of four blocks whose numerals have a 25 complementary relationship to the numerals on the first group of four blocks and which have designs thereon distinguishing them from each other but identifying them as a group, and a group of six blocks having 30 distinguishing designs thereon which indicate a relationship with respect to a plurality of the blocks of said two groups of four blocks.
5. A set of puzzle blocks comprising 35 blocks bearing on one face numerals representing successive terms of a recurring series, said blocks having on their faces opposite the numerals distinguishing designs having group characteristics identifying a 40 plurality of groups, the designs of the individual blocks of one group having characteristics indicating a mathematical relationship with respect to blocks of other of said groups. 45

In testimony whereof, I hereunto affix my signature.

FRANK S. GREENE.
